LIQUID COOING APPARATUS

Clyde P. Freer, Warren, Ohio, assignor to Halsey
W. Taylor Co., Warren, Ohio, a corporation of
Ohio

Application August 24, 1948, Serial No. 45,958

1 Claim. (Cl. 62—141)

1

My invention relates to liquid cooling apparatus, more particularly to water cooling apparatus such as drinking fountains, and the principal object of my invention is to provide new and improved apparatus of such character.

In liquid cooling apparatus, every effort is made to obtain maximum efficiency, so that input energy required to cool a certain amount of liquid is held to a minimum. When input energy is reduced, not only are operating costs correspondingly reduced, but by reason of increased efficiency, maintenance costs are also reduced.

Generally, my invention makes use of cooling energy which is normally wasted in the ordinary liquid cooling apparatus. More specifically, my invention utilizes the cooling effect of liquid passing through the exhaust outlet or drain to pre-cool incoming liquid flowing to the apparatus.

In the drawing accompanying this specification, and forming part of this application, there is shown, for purposes of illustration, an embodiment which my invention may assume, and in this drawing:

Figure 1 is a side elevational view of a water cooler of the drinking fountain type embodying my invention, with parts broken away and parts shown in section to better illustrate the invention.

Figure 2 is an enlarged fragmentary view of a portion of the apparatus shown in Figure 1, with a portion broken away to illustrate an interior construction, and

Figure 3 is a fragmentary sectional view corresponding generally to the line 3—3 of Figure 2.

Referring to the drawing, the embodiment of the invention herein disclosed is shown in use with a water cooler of the drinking fountain type, although it will be appreciated that my invention is not limited to the particular use disclosed.

The water cooler herein illustrated comprises a casing 10 enclosing at its lower portion an apparatus 11 such as the compressor-condenser unit of a usual refrigerator. Since the apparatus 11 may be of any well known type, detailed description thereof is believed unnecessary.

A water storage tank 12 is housed within the upper portion of the casing 10, this tank being adapted to contain a suitable supply of cooled water to meet demand requirements. A refrigerant coil 13 encircles the tank 12, and is in good thermal transfer relationship therewith, preferably by tinning the coil 13 to the exterior surface of the tank 12.

2

The inlet of the coil 13 is at the lower end of the tank 12, and is connected by a conduit 14 to the apparatus 11, and the outlet of the coil 13 is at the upper end of the tank 12 and refrigerant is returned to the apparatus 11 by means of a conduit 15.

Cooled water from the tank 12 is drawn off from the bottom of the tank 12 by means of a conduit 16 which leads to a valve 17. The valve 17 may be of any suitable construction, and as here shown is manually controlled by a rotatable hand piece 18. Water from the valve 17 is delivered to a bubbler 19 by means of a conduit 20.

15. In usual types of water coolers, the upper portion is provided with a depressed basin-forming portion 21, and to the lowermost part of this basin is connected the drain outlet 22. As herein shown, the outlet 22 is connected to an elbow 23 which in turn is connected to another elbow 24 by means of a short length of pipe 25.

Extending downwardly from the elbow 24 is a drain conduit 26 which connects to an elbow 27, the latter in turn being connected to a pipe 28 leading to a suitable drain.

In use of a water cooler such as herein disclosed, I have found that a user will open the valve 17 and let a certain amount of water flow from the bubbler 19 before taking a drink. Further, during the time the user takes a drink, quite frequently not all of the water flowing from the bubbler 19 is consumed. Also, there is a lag between the time the user completes his drink and the time the valve 17 is closed. All of the foregoing heretofore resulted in a waste of cooled water, since water flows to the drain and ordinarily performs no useful function.

My invention minimizes the waste before mentioned by utilizing the cooling effect of water flowing to the drain to pre-cool incoming water. In the embodiment herein shown, the incoming water is delivered to the water cooler by means of a conduit 30 which is connected to a suitable source of water supply.

45. The conduit 30 is connected to the bottom of a coil 31 which encircles the drain conduit 26 and is held in good thermal transfer relationship therewith, as by means of tinning or the like. The top of the coil 31 is connected to the inlet of the tank 12 by means of a conduit 32.

Within the drain conduit 26 is a means for establishing a trough of water, such means also providing a lip over which the water spills when drain water overflows the trough, the lip being so constructed and arranged that drain water is

caused to flow along the inner peripheral surface of the drain conduit.

In the embodiment herein disclosed, a ring-shaped element 35 is provided near the upper end of the drain conduit 26, such element being suitably secured in place, such as by welding, brazing, or the like. The element 35 is generally triangular in cross-section, the upper surface inclining downwardly toward the inner wall of the conduit 26, to form a trough 36. The opening 37 through the element 35 is defined by a conical surface which is of greater diameter at the bottom than at the top, the bottom diameter generally merging with the inner diameter of the conduit 26.

As cooled waste water flows from the drain outlet 22, it passes through elbow 23, pipe 25, elbow 24, and to drain conduit 26. This water will collect in the trough 36, until it overflows the trough, and then it will spill over the lip 38 and flow generally uniformly down over surfaces 37 of element 35 and the inner peripheral surface of the drain conduit 26.

Thus, the cool drain water is brought into intimate contact with the surface defining the drain conduit 26 so as to effect the ultimate in thermal transfer between cooled drain water and incoming water, and in such manner the incoming water is pre-cooled so that less energy is required to cool the water when it reaches the storage tank 12. In some instances, it may be desirable to use more than one element 35, and it is intended to include in this invention the use of one or more of such elements, the elements being disposed in series relationship with respect to the conduit 26 when more than one is used.

From the foregoing, it will be apparent to those skilled in the art that I have accomplished at least the principal object of my invention, and it also will be apparent to those skilled in the art that the embodiment of the invention herein described may be variously changed and modified, without departing from the spirit of the invention, and that the invention is capable of uses

and has advantages not herein specifically described; hence it will be appreciated that the herein disclosed embodiment is illustrative only, and that my invention is not limited thereto.

5 I claim:

A pre-cooler device for use in conjunction with a substantially vertically disposed drain pipe of a drinking fountain, said drain pipe having a supply pipe for drinking water disposed in a coil therearound, comprising a ring member of generally angular cross-section closely fitting within said drain pipe and having an upwardly and inwardly inclined top surface forming with the adjacent inner wall surface of said drain pipe an annular trough terminating in an inner elevated peripheral discharge lip disposed in a substantially horizontal plane, the lower wall surface of said ring member extending downwardly and outwardly from said lip and terminating closely adjacent the inner wall surface of said drain pipe, a portion of the chilled waste water entering said drain pipe being collected by said trough and discharged over said lip in a uniform peripheral overflow, a portion of said overflow water thereafter adhering to said lower wall surface of said ring member and thence adhering to the inner peripheral inner surface of said drain pipe and passing by gravity substantially directly downwardly therethrough, whereby drinking water in said supply pipe is initially pre-cooled by the chilled waste water adhering to and discharged through said drain pipe.
